COMBINATION CONTAINER AND ARTICLE HOLDER

John F. Skold, Chicago, Ill.

Application September 10, 1947, Serial No. 141,300

Term of patent 3½ years

(Cl. D58—12.6)

To all whom it may concern:

Be it known that I, John F. Skold, a citizen of the United States, residing at Chicago, in the county of Cook and State of Illinois, have invented a new, original, and ornamental Design for Combination Container and Article Holder, of which the following is a specification, reference being had to the accompanying drawing, forming a part hereof.

In the drawing:

The dotted lines shown in the drawing are for illustrative purposes only.

I claim:

The ornamental design for a combination container and article holder, substantially as shown and described.

JOHN F. SKOLD.
